UNITED STATES PATENT OFFICE.

JOSEPH GREENLEAF, OF ATLANTA, GEORGIA, ASSIGNOR TO NUNNALLY & McCREA CO., OF ATLANTA, GEORGIA, A COPARTNERSHIP COMPOSED OF CHARLES T. NUNNALLY, THOMAS H. McCREA, AND J. RUSSELL COMPTON.

GARMENT.

1,326,446.

Specification of Letters Patent. Patented Dec. 30, 1919.

Application filed May 2, 1917. Serial No. 165,916.

To all whom it may concern:

Be it known that I, JOSEPH GREENLEAF, a citizen of the United States, residing at Atlanta, county of Fulton, State of Georgia, 5 have invented certain new and useful Improvements in Garments, of which the following is a specification.

This invention relates to garments, particularly to overalls, and its object is to 10 provide an article of this class in which the supporting means comprises a pair of suspenders or shoulder straps detachably fastened to the body of the garment in front, in the usual manner, and so secured to the 15 rear portion of the garment body that the strain in the fabric due to the pull of the suspenders is well distributed instead of being excessive in one or two small portions, as in the garments of this character which 20 have heretofore been suggested.

The invention will be fully disclosed in the following description, taken in connection with the accompanying drawing, in which the garment is shown in perspective.

25 The body 10 of the garment is made in the usual manner with the exception of the rear upper portion 11 which tapers upwardly from the side openings to a point on the seat seam 12. The diagonal edges 13, 13 of the 30 tapering portion 11 are so inclined that the prolonged portions 14, 14 of the crossed suspender or shoulder straps 15, 15 lie therewith, and are secured thereto by stitching. In this way the two strips of material comprising the shoulder straps also form the 35 rear waist band.

The great advantage to be derived from this manner of construction over former constructions, where the shoulder straps 40 were both fastened to the body at the seat seam or where they were crossed and fastened at two distinct points, is that the pull of the shoulder straps is taken up by the

fabric of the rear upper portion of the body all of the way along the extended portions 45 14, 14 or waist band, and thus the garment is much stronger in this respect, and far more comfortable to the user, than the ones heretofore in use.

It will be noted that the suspenders continue along natural lines from their point of intersection to the side seams or side portions of the garment and that the upper edges of the rear portion of the garment extend inwardly and upwardly from the 50 side seams or side portions and meet at an angle at the intersection of the suspenders. The suspenders are connected to these edges and form a binding and finish therefor and the weight and strain upon the rear part of 60 the garment is distributed evenly from side to side thereof. The portions of the suspenders below the intersection are preferably of the same width as the other portions, giving the impression of continuous sus- 65 penders extending from the side seams over the shoulders.

Having thus described the invention, what is claimed and desired to be secured by Letters Patent is:

70 Overalls comprising a body and leg portions and suspenders, the upper edges of the rear or seat portion extending inwardly and upwardly from the side portions of the garment and meeting at an angle at the intersection of the suspenders and the suspenders being of substantially uniform width and 75 extending from said intersection along said edges to the side portions of the garment and being connected along their lower sides 80 to and forming a binding for said edges, whereby the strains of the suspenders are distributed over the rear part of the garment.

In testimony whereof I affix my signature. 85
JOSEPH GREENLEAF.
